UNITED STATES PATENT OFFICE.

HUGH OSWALD SHORT, OF ROCHESTER, KENT, ENGLAND.

LANDING AND LAUNCHING DEVICE FOR FLOATING STRUCTURES.

1,320,180.

Specification of Letters Patent. Patented Oct. 28, 1919.

Application filed March 22, 1919. Serial No. 284,422.

To all whom it may concern:

Be it known that I, HUGH OSWALD SHORT, a subject of the King of Great Britain, residing at Rochester, Kent, England, have 5 invented certain new and useful Improvements in Landing and Launching Devices for Floating Structures, particularly adapted for landing, launching, or loading hydro-aeroplane flying-machines or flying-boats, of 10 which the following is a specification.

In launching or landing hydro-aeroplane flying machines or flying boats as at present practised, a wheeled trolley is mounted on 15 rails extending from the shore to a sufficient distance and depth beneath the water, so that the trolley can be wheeled on the rails to a sufficient depth below the water level, and then the hydro-aeroplane flying machine or boat, hereafter termed the machine, is 20 floated to above the trolley, and the sides of the latter are secured to the hull or floats of the machine so that when the trolley is traversed shoreward the machine is brought to land. Certain disadvantages are however 25 incident to such an arrangement, in that for instance it is necessary for the attendants to enter the water to bring the trolley into position and secure it to the machine, which proceeding occupies a considerable time and 30 is dangerous.

Moreover it would frequently be convenient for the purpose of loading or otherwise giving attention to the machine if such operations could be carried out without it being necessary to bring the machine entirely ashore.

Now the object of the present invention is to provide a structure connected with the shore which will obviate the necessity of attendants entering the water for the purpose of securing the machine to the trolley and which structure will provide a floating platform or platforms upon which the attendants may stand not only for the purpose of 40 securing the machine to the trolley but also for loading and otherwise attending to the machine; and such platform or platforms can further be utilized by being partially submerged to permit a machine to be floated 45 over said platform and the platform then caused to rise and lift the machine from the water and the necessary operations having been carried out the platform or platforms 50 can again be submerged by mechanical action and the machine floated from off same.

The invention will be described further with reference to the accompanying drawings.

Figure 1 is a plan view showing an arrangement of a central slipway having four 60 rails to carry a trolley or trolleys and having a causeway on each side of the said slipway forming guides to laterally located pontoons.

Fig. 2 is a vertical section showing one of 65 the pontoons with a trailing gangway or footway for attendants to pass from the pontoon to the shore.

Fig. 3 is a sectional side elevation, and Fig. 4 is a transverse section, showing the 70 pontoon.

Fig. 5 is a transverse section showing a machine mounted on trolleys on the slipway, the machine in this instance being a twin flying boat.

Referring more particularly to Figs. 1 and 2 the inclined slipway 1, extending at a downward inclination from the shore to the requisite distance beneath the water, is fitted with rails to carry a trolley or trolleys, two 80 of which trolleys marked 3 are shown on the rails 2 at Fig. 5, and suitable means are provided, not forming part of this invention, by which the trolleys 3 can be traversed upon the rails.

At a distance on each side of the slipway is a causeway 4 extending at an inclination corresponding to the shore into the water for a sufficient distance and the causeway carries rails 5.

Each rail 5 supports a sliding carriage 6, Fig. 2, 3 and 4, which carriage 6 is fitted with wheels 7, bearing on the interior upper, or lower surfaces of the box section rails 5, Fig. 4, lateral wheels 8 being fitted to the carriage 6 to bear against the inturned edges of the box shaped rails, the carriage 6 as shown being of I section.

To the shore or inner end of the carriage 6, at 9 a pontoon 10 is pivoted, and the 100 outer end of the pontoon 10 and the outer end of the carriage 6 are connected by a flexible or elastic connection 11.

Hinged or pivoted at 12^x to the shore end of the pontoon, is a trailing gangway 12, 105 see Fig. 2, extending to the shore and resting upon the causeway 4, see particularly Figs. 1 and 2.

Where the shore is at a sufficiently steep inclination the carriage 6 to which the pon- 110

toon 10 is hinged, would rise or descend as the water level varied, and this action might take place practically automatically, but it is obvious that where the inclination is not sufficient or other circumstances obtain, the carriage 6 could be moved by suitable mechanical means, on the rails 5 so that the pontoon 10 was always maintained afloat.

Obviously the invention is not limited to 10 a definite construction of any one particular part but at Figs. 3, and 4, a construction is shown in which the pontoons are built up of lattice girders which support a deck 13, and mounted within the girder framework 15 are cylindrical air containing chambers 14.

A suitable motive power engine, not shown, can be carried for instance on the deck 13, to pump air into a suitable air pressure reservoir, which can be caused to communicate with the cylindrical chambers 14 controllable by suitable valves or cocks, and the chambers 14 may have apertures in their bases, so that by allowing of the exit of air from the pontoons, the platform or 20 deck 13 can be permitted to become submerged, and can again be floated by closing the air exits from the chambers or floats 14 and admitting thereto compressed air from the air pressure reservoir to cause the water 25 to leave the chambers 14 by apertures in the bases or lower parts thereof.

With such a structure as described a trolley or trolleys, such as 3, Fig. 5, can be traversed down the rails 2 of the slipway, 30 to between the pontoons 10, so that a machine can be brought up alongside the floating pontoon, or between the pontoons 10, the wings of the machine such as that shown at Fig. 5 extending over the pontoon decks 13 35 so that the hull or hulls or floats are brought within reach, and the sides of the trolley can then be fixed to the machine by attendants while standing on the pontoon decks 13, so that the machine can be brought out 40 upon the trolley or trolleys 3 and this without it being necessary for the attendants to enter the water. Moreover machines can be floated alongside the floating platforms or 45 pontoons for the purpose of loading or receiving other attention.

The floating pontoons are as aforesaid supported in the water by air containers or chambers 14 Fig. 3 into which water can be admitted as aforesaid to cause the outer end 50 of a pontoon to become more or less submerged, the said pontoon turning on the hinges 9 by which it is secured at the shore end to the carriage 6, and when in this position a machine can be floated on to the deck 60 of the pontoon if desired, and the water can then be forced or pumped out of the chambers 14 to cause the pontoon to rise, carrying with it the machine as shown at Fig. 2 which machine is then in a convenient position for 65 giving attention to the hull or floats, or for

loading the under part of the machine in any desired manner.

By fitting the slipway with four rails 2, at equal distance apart either two trolleys 3, may be employed as at Fig. 5, or only one 70 of the said trolleys, as at that figure, may be used, or a trolley of greater width may be carried of which the wheels bear upon an outer rail of one pair and an inner rail of the other pair. 75

What I claim as my invention and desire to secure by Letters Patent is:—

1. A landing and launching device for floating structures comprising in combination an inclined slipway extending to a sufficient distance beneath the water level, rails on the slipway, wheeled trolleys to run on said rails upon which trolleys a flying machine is to be carried, an inclined rail-carrying causeway or causeways on one or both sides of said slipway, a carriage to slide on said rails of each causeway, a floating pontoon, means for hinging the shore end of said pontoon to the shore end of said carriage to carry the attendants while securing said flying machine to said trolley or trolleys, and a trailing gangway pivotally connected to the shore end of the pontoon and resting with its opposite end on the said causeway to form a platform for the passage of the attendants to and from said pontoon. 90

2. A landing and launching device for floating structures; comprising in combination an inclined slipway extending to a sufficient distance beneath the water level, rails on the slipway, wheeled trolleys on said rails upon which trolleys a flying machine is to be carried, an inclined causeway on each side of said slipway extending beneath the water level, a carriage for each causeway, anti-friction wheels mounted on said carriage, rails mounted on said causeway said rails being of a section to be engaged by said wheels of said carriage to hold said carriage 105 to said rails, a floating pontoon, means for hinging the shore end of said pontoon to the shore end of said carriage, a trailing gangway, and means to pivotally connect said gangway to the shore end of the pontoon to permit the shore end of said gangway to rest on said causeway. 110

3. A landing and launching device for floating structures; comprising in combination an inclined slipway extending to a sufficient distance beneath the water level, rails on the slipway, wheeled trolleys on said rails upon which trolleys a flying machine is to be carried, an inclined causeway on each side of said slipway extending beneath the water level, a carriage for each causeway, anti-friction wheels mounted on said carriage, rails mounted on said causeway said rails being of a section to be engaged by said wheels of said carriage to hold said carriage 120 125 130

to said rails, a floating pontoon, means for hinging the shore end of said pontoon to the shore end of said carriage, a flexible connection to connect the outer floating end of 5 said pontoon to the outer end of said carriage, a trailing gangway, and means for pivotally connecting said gangway to the shore end of the pontoon to permit the shore end of said gangway to rest on said causeway.

4. A landing and launching device for floating structures; comprising in combination an inclined slipway extending to a sufficient distance beneath the water level, rails 10 on the slipway, wheeled trolleys on said rails upon which trolleys a flying machine is to be carried, an inclined causeway on each side of said slipway extending beneath the water level, a carriage for each causeway, 15 antifriction wheels mounted on said carriage, rails mounted on said causeway said rails being of a section to be engaged by said 20

wheels of said carriage to hold said carriage to said rails, a floating pontoon, means for hinging the shore end of said pontoon to the 25 shore end of said carriage, a flexible connection to connect the outer end of said pontoon to the outer end of said carriage, air containing float chambers in said pontoon, means for admitting water to or expelling 30 water from said float chambers to submerge the outer end of said pontoon or to cause said outer end to float, a trailing gangway, and means to pivotally connect said gangway to the shore end of the pontoon to permit the 35 shore end of said gangway to rest on said causeway.

In witness whereof I have hereunto set my hand in the presence of two witnesses.

HUGH OSWALD SHORT.
